UNITED STATES PATENT OFFICE.

JOSEPH W. LEE, OF RIVER FOREST, ILLINOIS, ASSIGNOR TO LEE GAS GENERATOR COMPANY, A CORPORATION OF ILLINOIS.

GAS-GENERATOR.

1,389,670.

Specification of Letters Patent. Patented Sept. 6, 1921.

Application filed October 31, 1917. Serial No. 199,552.

To all whom it may concern:

Be it known that I, JOSEPH W. LEE, a citizen of the United States, residing at River Forest, in the county of Cook and 5 State of Illinois, have invented certain new and useful Improvements in Gas-Generators, of which the following is a specification.

My invention relates to devices for vaporizing kerosene or other forms of petroleum 10 distillates, so as to convert the same into a gas, and has for its primary object the provision of a device of this character adapted for converting kerosene, for example, by vaporizing the same and effecting a complete 15 mixture of said vapor with the proper amount of air, into a fuel gas having all of the necessary properties which assure a perfect combustion.

Another object of the invention is to provide 20 a new and improved device of this character which will be simple in construction, which will minimize the consumption of fuel oil, and which will operate with a higher degree of efficiency than other known 25 devices of the above character.

Another object of the invention is to provide 30 novel means for automatically regulating the amount of gas generated by governing the amount of gas consumed.

Another object of the invention is to provide 35 a new and improved oil vaporizing device in which the amount of fuel oil admitted to the vaporizing chamber is automatically regulated, so that a substantially constant volume of oil will be maintained in said chamber throughout the entire operation of the device.

It has been found that a more complete and 40 satisfactory conversion of petroleum distillates may be accomplished by first vaporizing the oil and then subjecting the vapor to a higher degree of heat. Accordingly, my invention contemplates the provision of a new and improved device for carrying out 45 this process of converting oil into vapor. In this connection the invention has for a further and more specific object to provide novel means for increasing the temperature of said vapor prior to its introduction into 50 the mixing chamber, wherein it is mixed with the air, so that complete vaporization and thorough mixing of vapor and air will result, as will be hereinafter described.

Another object of the invention is to provide 55 a novel construction and arrangement

of the vapor and air ducts whereby the air introduced into the mixing chamber is brought into direct contact with the vapor, so as to effect the desired complete mixing of the air and vapor in the proper proportions to produce a fuel gas which is free from impurities and will be best adapted for heating or analogous purposes for which the gas may be used.

Another object of the invention is to provide 60 a novel valve construction in which any binding of the valve due to the contraction of the valve casing when the valve is closed is eliminated.

The invention has for further objects a 65 novel arrangement, construction and combination of parts hereinafter described and claimed, for carrying out the above stated objects, and such other objects as may appear in the following description.

The invention is illustrated in certain preferred embodiments in the accompanying drawings, wherein like characters of reference designate corresponding parts, and 70 wherein:

Figure 1 is a plan view of my improved gas generating device, illustrated in connection with a two-plate burner, and is of the type designed particularly to be applied to the fire box of a cook stove;

Fig. 2 is a vertical sectional view taken on line 2—2 of Fig. 1;

Fig. 3 is a cross-section taken on line 3—3 of Fig. 1, looking in the direction indicated by the arrows;

Fig. 4 is a sectional plan taken on line 4—4 of Fig. 2, and illustrating the preferred construction of the air inlet and mixing chamber employed in my invention;

Fig. 5 is an end view, partly in section, of 95 the device shown in Figs. 1 and 2, and illustrating the means employed for increasing the temperature of the oil vapor before its introduction into the mixing chamber;

Figs. 6 and 7 are views similar to Figs. 1 and 2, illustrating a modified form of the device;

Fig. 8 is an end view, partly in section, of 100 the construction illustrated in Figs. 6 and 7;

Fig. 9 is an enlarged sectional view of the 105 preferred form of needle valve employed for controlling the introduction of vapor into the mixing chamber of the device; and

Fig. 10 is a side view in elevation, illustrating the application of my invention to 110

the intake manifold of an internal combustion engine.

Referring first to Figs. 1 to 5, inclusive, of the drawings, in these figures the invention is illustrated in connection with a burner which is designed particularly to be applied to the fire box of a cook stove, for example. This particular form of burner is utilized merely for illustrating the principle of operation, and it will therefore be understood that I do not wish to limit myself to this particular use, as the device could obviously, with slight modifications, be employed for the purpose of generating gas for any of the well-known burners or other devices adapted to use gas of this character.

In the drawings, 10 designates a mixing chamber comprising a manifold 11 and an inlet passage-way 12. The inlet passage-way preferably communicates with the manifold near the center thereof, as indicated at 13, so as to provide an equal distribution of the gas among the several burners, as will be hereinafter described. The outer end of the member 12 is formed with a return or "goose-neck" bend 14 having an air inlet orifice 15 communicating with the inlet passage 12 through a port 16. The air passage is preferably formed in this manner so as to cause the air entering the passage-way 12 to intersect the path of travel of the vapor introduced into said passage from the vapor injector 17. The injector 17 extends through the wall of the inlet chamber adjacent the bend 14, and is arranged to project a jet of vapor into the inlet passage 12 with the proper velocity to induce the currents of air, illustrated in Fig. 4 by the semi-feathered arrows, to be drawn into the inlet passage 12 in the proper proportions to provide the desired mixture. The air and vapor, after being thoroughly mixed in this manner, enters the manifold 11 and passes through the discharge openings 18, 18, to the chambers 19, 19 formed by the burner plates 20, 20, which preferably fit over upstanding flanges 21 on the upper side of the manifold. The burner plates 20, 20, are provided with openings, preferably slits designated at 22, through which the gas escapes to the point where it may be ignited.

One of the principal ideas embodied in my invention is to first vaporize the kerosene, and then subject the vapor to a higher degree of heat immediately prior to its introduction into the mixing chamber. This process has been found to produce the best results for the reason that the complete conversion of the oil into vapor is assured before it is mixed with the air, and in this way the impurities, such as carbon, for example, are eliminated. In carrying out this process, I preferably provide a vaporizing vessel 23, which is adapted to contain a pre-

determined quantity of oil 24 to be vaporized, and is heated on its under surface by means of the pilot burner 25, which is provided with a plurality of small perforations 26 communicating with the interior of the manifold 11. The vaporizing vessel is preferably spherical in shape, and consists of an upper half 27 and a lower half 28 which are provided with suitable flanges and secured together as indicated at 29. 30 designates a gasket of suitable material, interposed between these attaching flanges so as to make a tight joint and thereby prevent any of the vapor generated in said vessel from escaping between the flanges. The lower half of the vessel 28 is preferably provided with a boss 31 which has a threaded engagement with a vertically extending feed pipe 32, so that the vaporizing vessel is supported in its operative position. The upper end of pipe 32 is closed by a plug 33 formed with a port 34 and with a concave surface 35, providing a suitable seat for the valve 36. The valve is provided with a stem which is held in a vertical position by means of a guide 37 formed on the inner surface of the upper half of said vessel. 38 designates a float of any suitable construction, preferably a hollow sphere, which is secured to the valve stem 39 so as to bring the valve 36 against its seat 35 when the oil 24 has reached a predetermined level in the vaporizing vessel. As the oil in the vessel is vaporized, the float moving downward will move the valve 36 away from the seat and open the port 34, so as to permit a sufficient amount of oil to be introduced into the vaporizing vessel to maintain the oil at the desired level. If desired, a spring 40 may be inserted in the guide 37 so as to bear against the upper end of the valve stem to assist in opening the valve, although this will ordinarily be unnecessary, as the pressure of the gas generated in the vaporizing vessel will be sufficient to counterbalance the oil pressure in the pipe 32 against the under surface of the valve 36.

41 designates a duct leading from the upper portion of the vaporizing vessel to the vapor injector 17. The vapor injector consists of a casing surrounding a needle valve 42, and is preferably provided with an enlarged space or pressure chamber 43 (Fig. 9) which converges as indicated at 44 toward the discharge opening 45, the taper of duct 44 corresponding to the taper 46 of the needle valve 42. The needle valve is preferably made of material having a slightly greater coefficient of expansion than the casing 17, so as to prevent any binding of the needle due to the contraction of the 125 casing when said valve is closed.

For the purpose of increasing the temperature of the vapor at the point where it is introduced into the mixing chamber, I preferably provide a burner 47 which is threaded 130

into the manifold, as indicated at 48, and provided with a series of openings 49, adapted to direct a flame against the portion 50 of the duct 41.

5 Operation: The device is started by heating the vaporizing vessel with a torch or by inserting waste saturated with oil into the cup-shaped pilot burner 25, so as to start the generation of vapor in said vessel. The 10 needle valve 42 is then opened, which permits the vapor to pass into the mixing chamber and mix with the air drawn into said chamber through the "goose-neck" air passage 14. The vapor and air then pass into 15 the manifold and escape through the apertures 26 of the pilot burner, projecting a flame against the under surface of the vaporizing vessel. The lower half of said vaporizing vessel, being convex, exposes a 20 large area of said vessel to the flames of the pilot burner, and in this manner provides for a rapid generation of vapor. A portion only of the gas is consumed by the pilot burner. The rest will pass through the 25 charge openings 18 to the point or points where it is to be used, such for example, as the burners 20, illustrated in Figs. 1 to 5, inclusive.

The oil is introduced into the vaporizing 30 vessel under pressure. The float valve 38 will rise and fall, so as to maintain a substantially constant volume of oil in said vessel. The vapor is preferably discharged into duct 41 from the upper half of the 35 vaporizing vessel, and this prevents any unvaporized oil or foreign matter, such as scale or sediment, for example, from being carried out along with the vapor in a manner to interfere with the proper operation of the 40 valve.

In Figs. 6 to 8, inclusive, I have shown a modified form of the device in which the gas is generated in a tube 51 which is supported above a priming cup 52 on the side 45 of the manifold 11^a. The tube is adapted to contain an absorbent material 53, which may be saturated with oil for the purpose of starting the generation of vapor in substantially the same manner as described in 50 connection with Figs. 1 to 5, inclusive. The manifold 11^a in this modified construction is preferably provided with a series of small apertures 54, adapted to direct a plurality of small flames against one side of the tube 51, in substantially the same manner as is described in connection with the operation of the pilot burner illustrated in Figs. 1 to 5. In other respects, this device is substantially the same as that described in Figs. 1 55 to 5, inclusive, and the parts thereof have been designated with corresponding reference characters.

In Fig. 10 I have shown a vaporizing and mixing device constructed in accordance with my invention, suitable for use as

a carburetor for an internal combustion engine, the inlet manifold 55 of which is shown in this figure. In this construction, all of the elements for accomplishing the vaporization and mixing of the fuel are substantially the same as those described in Figs. 1 to 5, inclusive, with the exception of the manifold 11^b, which in this case is provided with an upward bend 56 and formed with suitable flanges 57, adapted to be secured to 75 the engine manifold 55. The operation of this device will be the same as that set forth in connection with the description of Figs. 1 to 5, inclusive, and need not be again described in this connection. 80

I claim:

1. In a gas generator of the character described, the combination of a substantially spherical vaporizing vessel, a valve, a substantially spherical float arranged in said vaporizing vessel and connected to said valve so as to maintain a substantially constant volume of oil in said vessel, a burner adapted to apply heat to said vessel, and a duct communicating with said vessel above 85 the normal level of the oil and adapted to supply said burner with fuel.

2. In a gas generator of the character described, the combination of a substantially spherical vaporizing vessel, means for maintaining a substantially constant volume of oil in said vessel regardless of pressure conditions in said vessel, a mixing chamber, a duct communicating with the upper portion of said vessel adapted to conduct the vapor 90 therefrom into said mixing chamber, and a burner adapted to apply heat to said oil. 95

3. In a gas generator of the character described, the combination of a substantially spherical vaporizing vessel, means for maintaining a substantially constant volume of oil in said vessel, a mixing chamber, a duct communicating with the upper portion of said vessel adapted to conduct the vapor 100 therefrom into said mixing chamber where- 105 in it is thoroughly mixed with air, and a burner communicating with said mixing chamber and adapted to apply heat to said oil. 110

4. A gas generator of the character de- 115 scribed, the combination of a manifold formed with a plurality of burners, a mixing chamber communicating with said manifold and with the atmosphere, a vaporizing vessel adapted to be heated by one of 120 said burners, means within the vessel for maintaining a substantially constant volume of oil therein, a duct communicating with said vaporizing vessel and adapted to conduct vapor therefrom to the mixing 125 chamber, and a burner communicating with said manifold and adapted to heat said vapor adjacent the point where it is introduced into said mixing chamber. 130

JOSEPH W. LEE.
